[57] CLAIM

The ornamental design for a telephone apparatus housing, as shown and described.

DESCRIPTION

FIG. 1 is a perspective view of the base and raised handset of the telephone apparatus housing, showing my new design;

FIG. 2 is a perspective view of the base and handset of FIG. 1, showing the handset in position on the base; FIG. 3 is a top plan view of the base and handset of FIG. 2;

FIG. 4 is a bottom plan view of the base;

FIG. 5 is a front elevation of the telephone apparatus housing, according to FIG. 2;

FIG. 6 is a rear elevation thereof;

FIG. 7 is a right side elevation thereof;

FIG. 8 is a left side elevation thereof;

FIG. 9 is a bottom view of the handset;

FIG. 10 is a top plan view thereof;

FIG. 11 is a right side elevation thereof;

FIG. 12 is a left side elevation thereof;

FIG. 13 is a rear elevation thereof;

FIG. 14 is a front elevation thereof;

FIG. 15 is a top plan view of the base;

FIG. 16 is a front elevation thereof;

FIG. 17 is a rear elevation thereof;

FIG. 18 is a right side elevation thereof; and,

FIG. 19 is a left side elevation thereof.

The base unit in FIGS. 4 and 15-19 and the handset in FIGS. 9-14, have been shown separately for convenience of illustration.
